DESIGN FOR A LAPEL CLIP

Margery Cummings, Beverly Hills, Calif.

Application February 6, 1941, Serial No. 98,796

Term of patent 3½ years

To all whom it may concern:

Be it known that I, Margery Cummings, a citizen of the United States of America, residing in Beverly Hills, county of Los Angeles and State of California, have invented a new, original, and ornamental Design for a Lapel Clip, of which the following is a specification, reference being had to the accompanying drawing, forming part thereof, wherein,

I claim:

The ornamental design for a lapel clip, substantially as shown.

MARGERY CUMMINGS.
